W. J. WOOD.

WATER BACK FOR STOVES OR RANGES.

(Application filed May 12, 1900.)

(No Model.)

UNITED STATES PATENT OFFICE.

WALTER J. WOOD, OF ATLANTA, GEORGIA.

WATER-BACK FOR STOVES OR RANGES.

SPECIFICATION forming part of Letters Patent No. 656,687, dated August 28, 1900.

Application filed May 12, 1900. Serial No. 16,451. (No model.)

To all whom it may concern:

Be it known that I, WALTER J. WOOD, a citizen of the United States, residing at Atlanta, in the county of Fulton and State of Georgia, have invented new and useful Improvements in Water-Backs for Stoves or Ranges, of which the following is a specification.

This invention relates to certain new and useful improvements in stoves and ranges, the object being to provide a stove or range with a water-back which can be removed entirely from the stove without separating it from the stand-boiler, which object is accomplished by the employment of swinging joints or couplings which are arranged on a vertical line with each other and are interposed immediately between the water-back and stand-boiler, the present invention being designed more particularly as an improvement upon my Patent No. 646,779, patented April 3, 1900, and by the construction and arrangement of the parts as herein shown I am enabled to dispense with telescopic couplings and the packings incident thereto.

This invention consists in the combination with a stove or range having an opening through one of the side walls thereof, a door for closing the opening, a stand-boiler, and a water-back connected to each other by pipes and swing-joints, the stove or range, the stand-boiler and the water-back being so positioned one relative to the other that the water-back can be swung into the fire-pot or away from the same to entirely separate it from the stove or range.

My invention further consists in the arrangement of the parts and in the construction of the stove or range, as will be herein-after set forth, so that the only movement of the water-back will be in the arc of a circle, thus permitting the stand-boiler to be set up much nearer to the stove or range than it could be done with the arrangement illustrated in the patent hereinbefore referred to.

In the accompanying drawings, Figure 1 is a perspective view showing one arrangement of my invention. Fig. 2 is a detail view showing the rear portion of a stove or range with a slide which is used in connection with the door shown in Fig. 1. Fig. 3 is a detail sectional view taken vertically through the door

of the stove. Fig. 4 is a plan view showing a modified form of my invention. Fig. 5 is a sectional view through a swing-coupling which is provided with a cut-off. Fig. 6 is a perspective view of a drop-door which can be used in lieu of the horizontally-swinging door shown in the other views.

The stove or range A, as to its general construction, may be of the ordinary type; but, as shown in Fig. 1, the side wall of the stove and a part of the back wall is cut away to expose the fire-pot and permit of the placing therein of a water-back B. The opening through the side wall of the stove is closed by a door C, which is hinged to the stove and has at its end farthest from the hinges a part C', which projects at right angles to the main portion of the door, and said part C' has recesses c c, into which tongues a a of a slide A' will project when the door C is closed. The slide A' may be movably connected to the rear wall of the stove by bolts, which pass through slots in the slide, and the door may have a suitable latch or equivalent means for keeping the same closed.

As the door is intended to serve as one of the walls of the fire-pot when the water-back is removed therefrom, I prefer to construct the door so that it will be convex on its inner surface, such construction enabling the door to better resist pressure from within, and if an ornamental appearance is desired I may attach an ornamental plate to the convex plate of the door and have through said plate perforations, so an air-space will be present between the inner and outer plate. The recesses c c in the door C are on the same horizontal plane as the inlet and outlet pipes of the water-back.

The stand-boiler D is set up near the stove or range and pipes d d' extend from the usual points, and to the ends of said pipes are attached one of the sections of swing joints or couplings, the other section of said joint or coupling being attached to the inlet and outlet pipes b b', which project from the water-back. These short pipes and swing-couplings provide the sole means for connecting the stand-boiler with the water-back, and the swing-couplings E E may be constructed so that when the water-back is swung to a certain point, which may be indicated upon the

sections of the couplings, the water will be cut off from between the stand-boiler and water-back. By such an arrangement should an accident happen to the water-back the 5 water-supply thereto can be readily cut off and another water-back attached without in any way disturbing the water-supply. The swing joints or couplings are positioned in a vertical line with each other and are so placed 10 with respect to the stove that when the water-back is swung in a horizontal plane in one direction it will be placed in the fire-pot and will form one of the walls thereof, and said water-back may be covered by the door, 15 which overlies the side and rear end of the water-back, and when in place the pressure from within upon the water-back will be resisted by the door which covers the same, the greatest pressure upon the door being near 20 its hinges, the outer pressure at the other end being resisted by the couplings, which prevent any movement of the water-back except in the arc of a circle and in a horizontal plane. The recesses *c c* in the door partially 25 surround the pipes *b b'*, and said pipes by abutting against the tongues force the slide *A'* rearward. The door not only covers the opening in the side wall of the stove or range, but also the cut-away portion of the rear wall, 30 and permits a slight circulation of air between the end of the water-back and the angular part of the door sufficient to obviate warping of that part of the door.

In Fig. 4 of the drawings I have shown an 35 arrangement whereby the water-back is inserted in the stove from the front, and it will be noted that such arrangement provides a water-back which occupies the rear portion of the fire-pot and the outer end portion 40 thereof and that there is no possibility of the fuel coming in contact with the angular end of the door. This arrangement also permits the use of a drop-door instead of one that swings horizontally.

45 It will be noted in every instance that the only range of movement that the water-back has in placing the same within the fire-pot or in removing the same from the stove or range is a horizontal movement in the arc of a circle of which the center of the couplings is the center of the arc, and by such construction and arrangement the position of the stand-boiler may be varied to suit the requirements as to space and the position of the 50 boiler. By lengthening or shortening the pipes the boiler may be placed either close to the stove or range or close to the wall, whereas in my prior patent it was necessary, by reason of the construction illustrated therein, to 55 provide for a movement of the water-back greater than its length before the same could be entirely removed from the stove.

Having thus described my invention, what I claim as new, and desire to secure by Letters 60 Patent, is—

1. In combination with a stove or range having an opening through one of the side

walls thereof, a door for closing the opening, a stand-boiler having a water-back connected directly thereto by swinging couplings so as 70 to be moved into the fire-pot of the stove, the door being adapted to close the opening through the wall of the stove and when the water-back is removed from the fire-pot to form one of the walls thereof, substantially 75 as set forth.

2. The combination with a stove or range and its fire-pot, of a water-back, stand-boiler, and means for connecting the water-back to the stand-boiler said means comprising pipes 80 and interposed swing-couplings, an opening through an exterior wall of the stove of a size to admit the entrance of the water-back to the fire-pot, a door secured to the stove adjacent to the opening, said door serving to 85 hold the water-back in the fire-pot and form one of the walls of the fire-pot when the water-back is swung beyond the stove, substantially as shown.

3. In combination with a stove or range 90 having an opening through one of the outer walls thereof, a door attached to the stove to close the opening and serve as one of the walls of the fire-pot, of a water-back having pipes and swing-couplings, the pipes being of such 95 a length and the couplings being so positioned with respect to the fire-pot and the opening through the wall of the stove that the water-back may be swung into the fire-pot or entirely beyond the stove, substantially as 100 shown.

4. In combination with a stove or range, having an opening through one of the exposed walls thereof which opening is adjacent to the fire-pot, a door for closing said opening 105 and when closed providing a wall for the fire-pot, of a stand-boiler and water-back connected to each other by pipes and swing-couplings as shown, the length of the pipes and position of the swing-couplings being 110 such that the water-back may be swung horizontally into the fire-pot or entirely beyond the stove or range, for the purpose set forth.

5. The combination with a stove or range, having an opening through one of its exposed 115 walls, a door therefor hinged to the stove said door having a fire-wall, of a stand-boiler, water-back, pipes and swing-couplings with cut-offs for connecting the water-back with the boiler, the swing-couplings being so positioned 120 that the water-back may be swung horizontally into the fire-pot of the stove and be retained therein when the door is closed or swung beyond the stove, one position of the water-back when beyond the stove cutting off the water-supply, other positions permitting a circulation of water between the stand-boiler and the water-back, substantially 125 as set forth.

6. The combination in a stove or range having 130 an opening in one of its exposed walls, a door hinged to the stove and adapted to close the opening said door having a concave plate which serves as a wall for the fire-pot, of a

stand-boiler and water-back connected by pipes and swing-couplings so that the water-back may be swung through the opening into the fire-pot and when therein will be engaged by the plate attached to the door, substantially as shown and for the purpose set forth.

7. In combination with a stove or range having an opening through one of the side walls thereof and adjacent to said opening a 10 slide with tongues, a door hinged to the stove said door having a projecting end portion with recesses, of a stand-boiler and a water-back connected thereto by pipes and swing-couplings so that the water-back may be 15 swung into the fire-pot of the stove, the recesses in the projecting portion of the door partially surrounding the inlet and outlet pipes of the water-back, the tongues of the slide filling the recesses when the water-back 20 is positioned beyond the stove and the door is closed, substantially as shown.

8. In combination with a stove or range having an opening through one of the side walls thereof, a door hinged to the stove for 25 closing the opening, said door on the end opposite the hinges having a projecting portion with recesses, a stand-boiler having a water-

back connected directly thereto by swinging couplings so as to be moved horizontally in the arc of a circle into the fire-pot of the stove, 30 the door being adapted to close the opening through the wall of the stove and retain the water-back in the stove, substantially as shown and for the purpose set forth.

9. In combination with a stove or range 35 having an opening through one of the side walls thereof, of a stand-boiler and a water-back connected to each other the connecting means including swinging couplings, whereby the water-back may be swung into the 40 fire-pot or beyond the stove, a door hinged to the stove to close the opening leading to the fire-pot said door having a portion which projects at right angles and is recessed to partially surround the inlet and outlet pipes of 45 the water-back, substantially as shown.

In testimony whereof I have hereunto set my hand in presence of two subscribing witnesses.
